UNITED STATES PATENT OFFICE.

BRUCE K. INGLIS, OF MILWAUKEE, WISCONSIN, ASSIGNOR OF ONE-HALF TO CLEMENT W. INGLIS, OF MILWAUKEE, WISCONSIN.

OIL BURNER.

Application filed June 25, 1923. Serial No. 647,674.

This invention relates in general to improvements in the art of heating, and relates more specifically to improvements in the construction and operation of automatic fuel burners especially adapted for utilization in furnaces or boilers such as are ordinarily employed to heat dwellings and other buildings.

An object of the invention is to provide a fuel burner which is simple in construction and efficient in operation. Another object of the invention is to provide an improved oil burner which is compact in construction and which is reliable and automatic in operation. A further object of the invention is to provide an air operated rotary burner which will effectively produce and distribute a combustible mixture of fuel and air. Still another object of the invention is to provide an oil burning device which may be readily manufactured and conveniently installed either in new or existing heaters. Another object of the invention is to provide simple, efficient and automatically acting means for lubricating the bearings of oil burner mechanism and for maintaining such apparatus in operating condition. These and other objects and advantages of the present invention will be apparent in the course of the accompanying description.

A clear conception of several embodiments of the present invention and of the operation of apparatus constructed in accordance therewith, may be had by referring to the drawing accompanying and forming a part of this specification, in which like reference characters designate the same or similar parts in the various views.

Fig. 1 is a top view of an improved oil burner having a rotor operable by a current of air created by a blower, a portion of the rotor having been broken away in order to more clearly disclose details of the rotor structure.

Fig. 2 is a fragmentary vertical sectional view of the improved oil burner having its rotor operable by a current of air produced by a blower.

Fig. 3 is a fragmentary vertical sectional view of an improved oil burner the rotor of which is operable by a current of air created by the natural draft existing in the heating apparatus.

The improved oil burner illustrated in Figs. 1 and 2, comprises a stationary base

4 adapted for location within the lower portion of the combustion chamber of a heater 5, a rotor 2 rotatably supported concentrically of the base 4, a motor driven blower 19 for supplying air under pressure to the burner, a supply pipe 9 for supplying oil or other liquid fuel to the burner, a pipe 30 for supplying gas to the pilot light 16, and mechanism for controlling the supply of oil and gas.

The base 4 is preferably formed of cast metal and has an annular air supply chamber formed in its lower portion and communicating with the blower 19 through a tangential air supply pipe 31. The annular air supply chamber formed in the base 4 is accessible by virtue of a removable bottom plate 32. The central portion of the stationary base 4 is provided with a cup shaped recess 11 the lower extremity of which is closed by a removable plug 33 which forms a support for the vertical rotor shaft 3. The plug 33 also has a ball thrust bearing 14 therein upon which the shaft 3 rests, and serves to clamp the bottom plate 32 in position. The annular air supply chamber communicates with the recess 11 through a series of tangential passages 13. The peripheral portion of the base 4 is provided with an annular recess 17 and an upwardly diverging wall.

The fuel feeding and distributing rotor 2 comprises a dished disk secured to the upper end of the vertical shaft 3 and an annular bladed element suspended from the periphery of the disk to form an annular peripherally open fuel and air feeding gap. The lower portion of the annular bladed element is provided with a series of substantially radial blades 12 located within the recess 11 and in the horizontal plane of the tangential air supply passages 13. The central portion of the bladed element is provided with an annular continuous fuel receiving groove 7 the outermost portion of which communicates with the fuel and air feeding gap of the rotor 2 through a series of upwardly and outwardly directed fuel discharge openings 8. A continuous annular atomizing screen 6 surrounds the fuel and air feeding gap of the rotor 2, this screen preferably being secured directly to the rotor periphery.

The motor driven air supply blower 19 is preferably driven by an electric motor the

operation of which may be controlled by means of a switch 27 or other automatic control means. The discharge end of the fuel or oil supply pipe 9 is provided with a nozzle 10 or other means for conducting the oil into the groove 7 of the rotor 2. The supply pipe 9 communicates with a float control device 21 to which the supply of oil is delivered from a suitable storage tank through a main supply pipe 25 and a control valve mechanism 24. The pilot light 16 receives a regulated quantity of gas through the supply pipe 30 having an expansion coil 29 therein. The supply of air, oil and gas may be automatically controlled by a thermostat controlled regulating motor 26 direct connected to the control switch 27 and valve mechanism 24 and having its terminals 28 connected to the thermostat in a well known manner.

The lower portion of the recess 11 is provided with a drain pipe 15, the end of which is preferably disposed slightly above the bottom of the recess 11 in order to form an oil catch basin at the lower extremity of the recess. This basin may be connected with the upper bearing of the shaft 3 by means of a wick 1, and with the ball thrust bearing 14 by means of one or more oil feed openings. A vertical oil drain pipe 18 connects the annular recess 17 of the base 4 with the pipe 15 and the pipe 15 communicates through a bend 20 with a safety control mechanism 22 comprising a pan and a lever 23 adapted under abnormal conditions of operation to stop delivery of air, oil and gas to the burner.

In the modified form of burner disclosed in Fig. 3, a stationary base 34 is adapted for location within the lower portion of a heater 35, and a rotor 2 of modified construction is mounted centrally within the base 34. The base 34 has an annular lower recess 40 which communicates with a central upper recess 36 of the base through a series of tangential air admission openings 38. The rotor 2 is provided with a series of substantially radial blades 37 located adjacent to the delivery ends of the openings 38. The remaining elements of the structure are substantially similar to those of the apparatus disclosed in Figs. 1 and 2 and the base 34 is preferably provided with an annular peripheral recess 39 as shown.

During normal operation of the burner disclosed in Figs. 1 and 2, the terminals 28 of the regulating motor 26 are connected to a thermostat at the source to be heated in a well known manner, the thermostat being adjusted to start the motor 26 when a predetermined minimum temperature exists at the source, and to stop the motor when a predetermined maximum temperature has been established. When the regulating motor 26 is operating, oil is being ad-

mitted from the supply reservoir through the supply pipe 25, valve mechanism 24, float control device 21, pipe 9 and nozzle 10 in regulated quantity, to the annular groove 7 of the rotor 2. The motor of the blower 19 is in operation and air under pressure is being forced tangentially through the pipe 31 into the annular air chamber in the base 4. The air thus admitted to this annular air chamber whirls about the wall of the recess 11 and is eventually delivered at high velocity through the tangential passages 13 and against the blades 12 of the rotor 2. A rapid rotary motion is thus imparted to the rotor 2 by the entering air which after leaving the blades 12 passes through the recess 11 and is eventually diverted upwardly toward the top disk of the rotor 2. The rotor top disk causes the air to flow radially outwardly through the rotor feed gap where the air is intimately mixed with oil which is forced upwardly into the gap through the passages 8 from the groove 7 by centrifugal force. The mixture of oil and air is eventually delivered through the screen 6 in atomized condition and the atomized mixture is automatically ignited by contact with the gas pilot light 16. The annular flame produced by ignition of the atomized mixture of oil and air is delivered against the heat transfer surfaces of the heater 5 from whence the heat is conducted to the source to be heated, in a well known manner. As the predetermined maximum temperature is established at the source, the thermostat automatically becomes effective to stop the regulating motor 26 thus stopping the blower 19 and the delivery of oil through the nozzle 10, but maintaining the gas pilot light 16 in readiness for subsequent operation of the oil burner.

During normal operation of the modified burner disclosed in Fig. 3, the use of a blower and gas pilot light are unnecessary and it is preferable to maintain the burner in continuous operation. The modified burner is started by depositing a quantity of highly flammable oil or other substance in the depression in the top disk of the rotor 2 and possibly also in the lowest portion of the recess 39, and igniting this substance to create a natural draft of high velocity through the burner and heater. When a suitable draft has been thus created, air passes at high velocity through the recess 40 and passages 38 and is delivered tangentially against the blades 37 of the modified rotor 2. The air thus impinging against the rotor blades 37 produces rapid rotation of the rotor. Fuel oil admitted in regulated quantity through the pipe 9 and nozzle 10 is mixed with air passing through the rotor gap and the mixture of air and oil is eventually delivered in atomized form past the screen 6 of the rapidly revolving

rotor whereupon the mixture is automatically ignited by contact with the flame produced by ignition of the starting substance. When the modified burner has been thus placed in operation, and if the supply of oil is properly maintained, the operation will automatically continue and the burning mixture of fuel oil and air will maintain the draft necessary to produce rotation of the rotor 2. In order to interrupt the operation of the modified burner, it is only necessary to stop the delivery of fuel oil, and such stoppage may be readily effected with the aid of an automatically functioning thermostat or the like.

It will be noted that if for any reason, the flame necessary to maintain ignition of the mixture of oil and air delivered from the rotor 2 is extinguished, and the flow of fuel oil continues, the excess oil will soon flow from the recesses 17, 11, 39, 36 through the pipes 18, 15 to the safety control mechanism 22 and will automatically prevent further feeding of oil and air to the burner. Any excess oil which is deposited in the recess 11, 36 serves to effectively lubricate the bearings of the rotor shaft 3 which are located where the entering air automatically serves to keep them cool. The rotor 2 is of perfect dynamic balance and requires very little energy for its rotation. Complete withdrawal of oil from the central recess 11 is prevented by virtue of the fact that the end of the pipe 15 extends above the bottom of the recess 11, thereby insuring retention of sufficient oil to properly lubricate the bearing 14.

From the foregoing description it will be apparent that the improved burner is of extremely simple and compact construction and its efficiency has been demonstrated by its successful commercial operation. The operation of the burner is entirely automatic when normal operation has been established, and the entering air serves to effectively rotate the distributing and mixing rotor and also prevents overheating of the rotor structure. The apparatus may be readily manufactured and installed in any standard or special heating apparatus and effectively distributes the flame against the heat transfer surfaces of the heater.

It should be understood that it is not desired to limit the invention to the exact details of construction and of operation of apparatus such as herein shown and described, for various modifications within the scope of the claims may occur to persons skilled in the art.

It is claimed and desired to secure by Letters Patent:—

1. In combination, a rotor comprising vertically spaced walls forming an annular space surrounding and extending away from the rotor axis, an annular series of

blades surrounding said axis below said space, the discharge edges of said blades being in communication with the inlet of said space, means for directing air tangentially against said blades and toward said axis to rotate said rotor, and means for delivering oil directly into said space near the inlet thereof.

2. In combination, a rotor comprising vertically spaced walls forming an annular space surrounding and extending upwardly away from the rotor axis, an annular series of radial blades surrounding said axis below said space, the discharge edges of said blades being in communication adjacent to said axis with the inlet of said space, means for directing air tangentially against said blades and toward said axis to rotate said rotor, and means for delivering oil directly into said space near said axis.

3. In combination, a rotor having a top plate and a wall cooperating therewith to form an annular space surrounding and directed away from the rotor axis toward the periphery of said top, a series of blades surrounding said axis, the discharge edges of said blades being in communication with the inlet of said space, means for directing air inwardly against said blades to rotate said rotor, and means for delivering oil outwardly through said space.

4. In combination, a rotor having a top plate and a wall cooperating therewith to form an annular space surrounding and directed away from the rotor axis toward the periphery of said top, an annular series of blades surrounding said axis laterally adjacent to said space, the discharge edges of said blades being in communication with the inlet of said space, means for directing air tangentially against said blades and toward said axis to rotate said rotor, and means for delivering oil directly into said space near the axis of said rotor.

5. In combination, a rotor having a top plate and a wall cooperating therewith to form an annular space surrounding and directed upwardly away from the rotor axis toward the periphery of said top, an annular series of radial blades surrounding said axis below said space, the discharge edges of said blades being in communication adjacent to said axis with the inlet of said space, means for directing air tangentially and inwardly against said blades to rotate said rotor, and means for delivering oil directly into said space near said axis.

6. In combination, a base having central and peripheral recesses, a rotor mounted centrally within said central recess, said base being formed to direct air inwardly toward the axis of said rotor to produce rotation thereof, means for admitting oil to said rotor within said central recess, common means for withdrawing surplus oil from

both of said recesses, and for preventing complete withdrawal of oil from said central recess.

7. In combination, a base having a recess, a rotor located within said recess, means for directing air inwardly toward the rotor axis to rotate said rotor, rotor supporting means located within said recess, means for delivering oil to said rotor,

said recess being formed to accumulate excess oil delivered to said rotor, and means for withdrawing oil from said recess and for preventing complete withdrawal of said oil.

In testimony whereof, the signature of the 15 inventor is affixed hereto.

BRUCE K. INGLIS.
